UNITED STATES PATENT OFFICE.

JAMES KIRKPATRICK, OF PHILADELPHIA, PENNSYLVANIA.

BLOCK-PRINTING MACHINE.

1,372,701.

Specification of Letters Patent. Patented Mar. 29, 1921.

Application filed April 14, 1920. Serial No. 373,914.

To all whom it may concern:

Be it known that I, JAMES KIRKPATRICK, a citizen of the United States, residing at Philadelphia, in the county of Philadelphia and State of Pennsylvania, have invented 5 certain Improvements in Block-Printing Machines, of which the following is a specification.

This invention relates to improvements in 10 block printing machines adapted for printing fabrics such as floor cloth, oil cloth and the like, and it comprises more particularly improved means for controlling the operations of the printing blocks in order to hold 15 them out of action and releasing them for action so that several blocks can be operated in a desired cycle or relation, as in printing so called rug designs for instance.

The characteristic features of the invention 20 are fully set forth in the following description taken with the accompanying drawings illustrating a form of the improved mechanism.

In the drawings, Figure 1 is a side elevation 25 of a section of a printing machine equipped with my improvements, Fig. 2 is a top plan view of detached elements of the machine, Fig. 3 is an enlarged broken side elevation of elements shown in Fig. 1 in different relations, and Fig. 4 is a broken sectional elevation of details of the construction.

The mechanism illustrated comprises the frame 1 provided with the vertical guides 2 35 for the slide bars 3 which carry the heads 4 having the printing blocks 5 fixed thereto. Cams 6 and 7, fixed on the respective transverse shafts 8 journaled in the frame, act 40 through rollers 9 on the bars 3 to operate them together with the heads and blocks carried thereby. The shafts 8 are operated together in any convenient manner as by providing them with the beveled gears 10 and driving these gears through the beveled 45 gears 11 fixed on journaled shafts 12, the shafts 12 being provided with spur gears 13 driven by spur gears 14 on a journaled longitudinal shaft 15.

Connected inking mechanisms 16 are movable 50 to and fro on the frame, under the blocks 5, to ink them, and clear thereof, to permit them to descend in the printing operation upon a fabric carried by the bands 17.

Dogs 18, fixed on the transverse shafts 19 55 journaled in the frame, are adapted to en-

gage lugs 20 on the bars 3 to hold the heads 4 together with the blocks 5 in the elevated position out of operation, the dogs being thrown into position for engaging the lugs 60 by weighted arms 21 on the respective shafts.

The foregoing mechanism, of usual construction, has, in accordance with my invention, arms 22 fixed on the respective shafts 65 19 and provided with rollers 23 which are held in engagement by the parts 21 with cam wheels comprising disks 24 provided with the under cut circular grooves 25 and cams 26 detachably connected with the disks in 70 symmetrical relation by the bolts 27 having their heads engaged in the slot. These cams 26 will be varied in character in accordance with the functions to be performed, so as to secure the desired relation between the 75 "dips" alternating with the lock-ups and obtain the desired operations of the respective heads in the desired relation. The disks 24 are fixed on shafts 28 journaled in the frame transversely thereof and revolved by the 80 beveled gears 29 fixed thereon, these gears being driven together by beveled gears 30 on a journaled shaft 31 extending longitudinally of the frame.

It will be understood from the foregoing 85 description that the improved mechanism, applicable to machines of various types, can be adjusted readily, by changing the cams to control the actions of the respective heads with the blocks thereon so that they will 90 operate in any desired relation in order to effect the desired impressions necessary for printing different designs.

Having described my invention, I claim:—

1. In a block printing machine, the combination with a plurality of reciprocatory printing mechanisms comprising heads provided with printing blocks, of locking mechanisms for holding said printing mechanisms out of action and means for operating said locking mechanisms, said means comprising journaled shafts provided with arms for rocking them, journaled shafts parallel to said shafts first named, means for revolving said shafts second named together, and adjustable cams on said shafts second named and adapted to act on said arms in predetermined relation through predetermined periods.

2. In a block printing machine, the combination with vertically reciprocatory slide bars provided with printing heads and co-

acting rotary cams for simultaneously elevating said bars with the heads thereon, of means for engaging said bars to hold said heads in elevated positions in predetermined relation, said means comprising rock shafts corresponding to the respective printing heads, latching devices on said shafts for engaging said bars to hold said heads in elevated positions, arms on said shafts, rotary devices having axes parallel to said shafts

and provided with changeable cams adapted to act through the respective arms and operate said latching devices periodically in predetermined relations, a journaled shaft transverse to said shafts first named, and means whereby said journaled shaft revolves said rotary devices.

In testimony whereof I have hereunto set my name this 13th day of April, 1920.

JAMES KIRKPATRICK.
